UNITED STATES PATENT OFFICE.

JAMES F. McELROY, OF ALBANY, NEW YORK, ASSIGNOR TO CONSOLIDATED CAR-HEATING COMPANY, OF ALBANY, NEW YORK, A CORPORATION OF WEST VIRGINIA.

HOT-WATER HEATING APPARATUS.

No. 831,735.

Specification of Letters Patent.

Patented Sept. 25, 1906.

Application filed April 28, 1902. Serial No. 104,978.

To all whom it may concern:

Be it known that I, JAMES F. McELROY, a citizen of the United States of America, and a resident of Albany, county of Albany, State of New York, have invented certain new and useful Improvements in Hot-Water Heating Apparatus, of which the following is a specification.

My invention relates to apparatus for heating by the circulation of hot water or other fluid, particularly adapted for use in railway-cars.

The object of my invention is to provide a means for supplying a solid column of water from the expansion-drum down through the downflow-pipe and for turning the hot water which rises from the heater into the downflow-pipe rather than causing the heated water to mingle with the water in the expansion-drum. I accomplish this object by means of the mechanism illustrated in the accompanying drawings, in which—

Figure 1 is an elevation with parts broken away. Fig. 2 is an elevation of the fitting T. Fig. 3 is a section of the fitting T and a portion of the expansion-drum. Fig. 4 is a cross-section along the line X X on Fig. 3. Fig. 5 is a section of the heating-drum V.

Similar letters refer to similar parts throughout the several views.

The radiator-pipes A are supplied with water by the downflow-pipe B and are connected by the pipe C with the heating-drum V or with a Baker heater, which may be substituted in place of the heating-drum V, if desired. The expansion-drum D connects with the downflow-pipe B by means of the fitting T, which fitting is preferably provided with a semicircular opening t, communicating with the expansion-drum D and with the pipe B. Within the fitting T, I arrange a chamber E, communicating with the pipe F, extending into the expansion-chamber D above the water placed therein, and also communicating with the pipe G, extending downward and communicating with the pipe B, but preferably disconnected therefrom. Around the pipe F, the chamber E, and pipe G the water from the expansion-drum will pass through the opening t into the pipe B, as shown in Fig. 3.

From the heating-drum V or the Baker heater, depending upon which of the two

mechanisms is used, the pipe H extends, communicating with the chamber E in the fitting T. The heated water passing through the pipe H to the chamber E flows downward through the pipe G into the pipe B and thence into the radiating-pipes. The steam in the hot water from the heater passing upward, being separated from the water in the chamber E, is delivered in the expansion-drum above the water, where it condenses, coming into contact, as it does, with the sides and top of the expansion-drum and the water therein. The steam thus delivered into the expansion-drum condenses very quickly and exerts no appreciable pressure upon the water therein. When the heater is in vigorous action, a portion of the steam may accompany the water a short distance downward from the chamber E into the pipe G before it escapes, and it is for this reason that I preferably extend the pipe G below the chamber E at a distance of about a foot.

By my apparatus the water in the expansion-drum does not become heated until after the circuit is obtained in the radiating-pipes and the steam rising from the heater does not enter the downflow-pipe, therefore cannot act as a check to circulation, as it would if it were allowed to mingle with the water in that pipe.

So far as I am aware, no other heating apparatus is provided with a means for separating steam from the water at the highest point of the circuit or for conveying steam to the space at the top of the expansion-drum without passing through the water in said drum.

By my apparatus I do away with the method heretofore employed in hot-water-circulating systems of heating the water in the expansion-drum, as it requires a considerable time to change the temperature of the water therein and the flow of hot water to the car in said method is always delayed on that account.

I have referred to the heating-drum as being one means for heating the water of circulation in my apparatus. Within the drum V, I place spurs J and K, preferably four, although but two are shown in the section, said spurs being secured at one end in the fitting L, connecting with the chamber l in said fitting, the steam-conveying pipe M commun-

cating with the pipe P, by means of which the steam is delivered to the spurs J and K and to the two other spurs. (Not shown.) The spurs are opened at their ends farthest from the fitting L, allowing the steam to pass through and to enter pipes N and O, which envelop said spurs and which are closed at their ends farthest from said fitting and which are secured to said fitting, communicating with the chamber R therein, said chamber R communicating with a pipe Q, which carries off the water of condensation from the pipes enveloping said spurs. The pipe C, communicating with the radiators, carries the water of circulation into the drum V, where it circulates and passing therethrough in contact with the pipes N and O, through which the steam from the spurs passes, and out through the pipe H, conveying the heated water and such steam as may be generated to the fitting T.

What I claim as my invention, and desire to secure by Letters Patent, is—

1. In a hot-water heating apparatus, a heater; radiator-pipes; an expansion-drum; a downflow-pipe; a fitting provided with a chamber; a pipe leading from said chamber to the expansion-drum; a pipe leading from said chamber to the downflow-pipe; a pipe leading to said chamber from said heater; a means for conveying water from the expansion-drum to said downflow-pipe, substantially as described.
2. In an apparatus for heating by the circulation of hot water, a heater; an expansion-drum; a downflow-pipe; radiator-pipes; a pipe-fitting; a pipe for conveying the water heated in said heater to said fitting; a means in said fitting for separating the steam from the water; a pipe for conveying the separated steam to the expansion-drum at a point above the water therein; a pipe for conducting the hot water from said fitting into the downflow-pipe, substantially as described.
3. In a hot-water heating apparatus, a heater; radiator-pipes; an expansion-drum; a downflow-pipe; a pipe-fitting connecting with said downflow-pipe near said expansion-drum; a pipe for conveying hot water from said heater to said fitting; a means in said fitting for separating the steam from said hot water; a pipe for conducting the steam thus separated to the expansion-drum above the water therein; a pipe for conducting the water from said fitting to said downflow-pipe, substantially as described.

5. In a hot-water heating apparatus, a downflow-pipe; a fitting provided with a heater; an expansion-drum; radiator-pipes; a chamber and with a passage-way communicating with the expansion-drum and with the downflow-pipe; a pipe communicating with said chamber and extending into the space above the water in said expansion-drum; a pipe also communicating with said chamber for conveying the hot water from the heater to the chamber; a pipe for conveying the hot water from said chamber into the downflow-pipe substantially as described.

6. In a hot-water heating apparatus, a downflow-pipe; a fitting provided with a heater; an expansion-drum; radiator-pipes; a chamber and with a passage-way communicating with the expansion-drum and with the downflow-pipe; a pipe communicating with said chamber and extending into the space above the water in said expansion-drum; a pipe also communicating with said chamber for conveying the hot water from the heater to the chamber; a pipe for conveying the hot water from said chamber into the downflow-pipe substantially as described.

7. In a hot-water heating apparatus, a heater; radiator-pipes; a downflow-pipe connected therewith; an expansion-drum; a heater consisting of a drum; a fitting connected with said drum a steam-chamber in said fitting to which steam is conveyed; a series of spurs communicating with said steam-chamber; a series of pipes enveloping said spurs respectively; a drip-chamber in said fitting to which said pipes are connected; a means for conducting the water of circulation to said drum and permitting the same to circulate in contact with said pipes; a pipe for conveying the water of circulation from said drum to a fitting attached to the downflow-pipe; a means in said fitting for separating the steam from the hot water; a pipe for conducting the steam from said fitting to the space in the expansion-drum above the water therein; a pipe for conducting the hot water from said fitting into the downflow-pipe, substantially as described.

Signed at Albany, New York, this 26th day of April, 1902.

JAMES F. McELROY.
